UNITED STATES PATENT OFFICE.

EARL L. GILLELAND, OF GRAND FORKS, NORTH DAKOTA.

TELEGRAPH INSTRUMENT.

1,179,517.

Specification of Letters Patent. Patented Apr. 18, 1916.

Application filed February 4, 1915. Serial No. 6,087.

To all whom it may concern:

Be it known that I, EARL L. GILLELAND, a citizen of the United States, residing at Grand Forks, in the county of Grand Forks and State of North Dakota, have invented certain new and useful Improvements in Telegraph Instruments; and I do declare the following to be a full, clear, and exact description of the invention, such as will enable others skilled in the art to which it appertains to make and use the same.

This invention relates to telegraphic instruments but more especially to those utilized for receiving purposes.

One object of this invention is to provide a telegraphic instrument of the character specified through the instrumentality of which the necessity for the usual local circuit and accompanying sounder therein is eliminated.

Another and further object of the invention is to provide a single instrument having a combined relay and sounder so associated as to be operated simultaneously.

Another and still further object resides in providing a combined relay and sounder having means by which the sounder if desirable may be eliminated and the relay used to control a local circuit and sounder therein as is now customary.

Another and further object is to provide a novel retractile means for the stop of the sounder as well as the armature of the relay and a final object is to produce a simple, easily constructed efficient and inexpensive instrument the sounder of which will operate as clearly and distinctly as it would if included in a usual local circuit.

With these and other objects in view, my invention consists of certain novel features of construction, combination and arrangement of parts to be more particularly hereinafter set forth and claimed.

In the accompanying drawings in which corresponding parts are indicated by similar reference characters: Figure 1 is a side elevation of my improved relay and sounder: Fig. 2 is a top plan view thereof: Fig. 3 is a central longitudinal section: Fig.

4 is a transverse vertical section taken on the line 4—4 of Fig. 1: Fig. 5 is a similar view taken on the line 5—5 of Fig. 1: and, Fig. 6 is a horizontal section taken on the line 6—6 of Fig. 3.

In the present system of telegraphy, a line circuit runs from station to station and

at each station inserted in the circuit is a relay. The armature of this relay operates a local circuit containing a sounder. This is done because usually the line circuit is necessarily weak and the relay must be very sensitive to respond to the signal. As a result the armature of the relay is very light and thin so that consequently its clicks are almost indistinguishable. Therefore it is necessary in order to clearly bring out the signal being conveyed to provide the above referred to local circuit and sounder. This local circuit and sounder, however, in many instances has proved disadvantageous in that new batteries must be provided occasionally and further when the set is initially installed an extra instrument is necessary, to wit: a sounder. Now it is to overcome the necessity for this additional sounder and circuit that I propose to provide a single instrument constituting a combined relay and sounder, the usual electromagnets of the latter however, being omitted, which relay and sounder are so connected mechanically as to operate simultaneously. Further I propose to have the stop of the sounder connected to the armature of the relay in such a manner that when the latter is actuated the stop will be brought into contact with its anvil so as to produce the various signals as clearly and distinctly as they would be produced if an ordinary sounder was employed.

In carrying out the foregoing I provide a pedestal 1 formed of metal, soap-stone or other suitable material and upon the upper surface of the pedestal 1 is disposed an insulating base 2 which carries the various parts constituting the relay under consideration. Two screws 3 pass through the base 2 at one end thereof and in spaced relation and are provided with threaded caps 4 forming binding posts to which are connected the leads from the main line. Two other screws 5 also pass through the base 2 at one side thereof and are provided with adjustable caps 6 forming binding posts for the leads of the local circuit when said circuit is desired.

Disposed upon the upper surface of the base 2 in suitable spaced relation to one end thereof is a frame 7 having therein the two annular openings 8 the diameter of which corresponds to that of the two electromagnets 9 which are slidably mounted in said openings. The frame 7 is provided

with suitable legs 10 which are secured to the upper surface of the base 2 as clearly shown in Figs. 1, 2 and 4. To the rear of the two electro-magnets 9 which in this instance are the usual 150 ohm relay magnets is a standard 11 having a transverse threaded opening through the upper end thereof. An adjusting screw 12 has its threaded shank 13 passed through the threaded opening in the standard 10 and engaged with a transverse bar 14 which connects the rear of the two electro-magnets 9. By this structure it will be seen that when the adjusting screw 12 is revolved the electro-magnets may be moved in and out of the openings 8 in the frame 7 as desired.

Secured to frame 7 are two adjusting screws 15 one of which is disposed contiguous to each of the legs 10 in insulated relation thereto. These adjusting screws 15 are arranged in horizontal alinement and have their inner ends concaved so as to receive the pronged extremities of a shaft 16 which passes through the apertured end of an armature 17. Said armature 17 consists of a central member 17' and a cross member 17'' which latter co-operates with the respective cores of electro-magnets 9 as clearly shown in Figs. 3 and 4.

The central upper portion of the frame 7 is provided with an extension 18 through which passes a transverse threaded opening 19 into which is threaded a set screw 20 for co-operation with the contact formed on the upper end of armature member 17'.

Immediately in front of the frame 7 upon the base 2 is mounted a plate 21 which carries a vertically disposed yoke 22 rising from one end thereof. Also upon plate 21 forward of yoke 22 is an anvil 23 having the usual set screw 24 the purpose of which will be hereinafter set forth. Extending transversely through the yoke 22 is a shaft 25. This shaft 25 passes through an opening formed in the inner end of a stop 26, and pivotally supports the same. Depending from the pivotal end of the stop 26 is an extension 27 which may be either integrally formed on the inner end of said stop 26 or may be secured to the latter by means of a central adjusting screw.

Passing through the lower portion of the extension 27 is a pin 28 to which is pivotally connected one end of the link 28' the other end of the latter being connected to a pin 29 which passes transversely through the upper portion of the armature member 17' so that whenever the armature is attracted by the electro-magnets 9 the link will be actuated and drawing on extension 27 will bring the stop 26 into contact with this anvil as will be readily understood without further description. To limit the downward movement of the stop 26 the latter is provided with an adjusting screw 30 where-

as the upward movement of said stop is limited by the adjusting screw 24 hereinbefore referred to. In order to restore the stop 26 to normal position after the latter has been actuated by the armature 17 there is provided a retractile spring 31 having an offset intermediate portion 31' which passes around one leg of anvil 23 and has one end connected to the lowered end of the extension 27 as at 32, whereas the other end projects through the remaining leg of the anvil 23 and is threaded to receive an adjusting screw 33 so that the tension on said spring may be regulated as desired.

In order to provide suitable circuit connections for the local circuit so that the latter may be employed when desirable one of the binding screws 5 is connected to the set screws secured to the frame 7 contiguous to the supporting legs thereof by a conductor 34 whereas the remaining binding screw 5 is connected by a conductor 35 to the set screw 20 so that whenever the armature member 17' contacts with said set screw the local circuit will be opened and closed as in the ordinary relay construction. However it is here to be noted that under ordinary circumstances the set screw 20 is unscrewed to such an extent that it does not project from the opening 18 in projection 19 and consequently under normal operation the armature member 17' does not contact with the inner end of said set screw but said armature simply actuates the stop 23 from which it will be apparent that said screw 20 is only brought into use when it is desirable to employ the relay for controlling a local circuit and sounder arranged in the latter. Local circuit can also be completed through sounding bar and anvil, if desired.

In order to connect the electro-magnets 9 to the line the latter are connected by conductors 36 to the two binding screws 3 as will be readily understood without further description.

Thus it will be seen that by the foregoing structure and arrangement of parts I have provided an extremely simple, efficient relay and sounder, the latter being so balanced as to be easily actuated by the armature of the relay to which it is connected so as to clearly and distinctly reproduce the transmitted signals.

Although by the foregoing I have described certain elements as best adapted to perform the functions ascribed to them nevertheless it will be understood that various minor details as to form, substance, etc., may be resorted to within the scope of the appended claim without departing from or sacrificing any of the principles of the invention.

I claim as my invention:

A device of the character described comprising a pair of electromagnets, an arma-

ture controlled thereby and pivoted at its lower end, a yoke-shaped member, a shaft carried by the latter, a stop pivotally secured at its inner end to said shaft, an anvil operatively disposed with respect to the free end of said stop and having two legs, the front leg having an opening therein, a depending extension formed on the inner end of said stop and spaced rearwardly of said anvil, a link connecting the lower end of said extension and the upper free end of said armature, a spring having one end threaded and extending through the opening in the front leg of said anvil, the inter-

mediate portion of said spring being offset 15 and extending around the rear leg of said anvil, the other end of said spring being connected to the lower end of said extension, and a nut disposed on the first named end of said spring, whereby to release said stop 20 to normal position after actuation thereof.

In testimony whereof I have hereunto set my hand in presence of two subscribing witnesses.

EARL L. GILLELAND.
